UNITED STATES PATENT OFFICE.

MARK G. MELVIN, OF SCRANTON, PENNSYLVANIA.

LIQUID-SOAP DISPENSER.

1,215,298.

Specification of Letters Patent. Patented Feb. 6, 1917.

Application filed August 24, 1915. Serial No. 47,090.

To all whom it may concern:

Be it known that I, MARK G. MELVIN, a citizen of the United States, residing at Scranton, in the county of Lackawanna and State of Pennsylvania, have invented new and useful Improvements in Liquid-Soap Dispensers, of which the following is a specification.

This invention relates to liquid soap dispensers and has for its primary object the provision of a device of this character in which a limited quantity of liquid soap may be discharged into the hand of the operator without the necessity of providing complicated and objectionable working valves.

A further object of the invention relates to the general simplicity of a structure of this character which will be positive in action and of a design which may be actuated with ease.

Another object of the invention is to provide a liquid soap dispenser and a discharge or dispensing device, both of which being designed so as to permit of their ready connection with one another at the time of filling the container and it is further desired and contemplated that the connection between the container and the dispensing member be such so as to cause a part filling of the dispensing member normally.

Another object of the invention is the provision of a dispensing device which will consist of a comparatively few parts and means for effecting a liquid tight joint between the parts when the dispensing member is in a discharge position.

It is further desired that provision be made for restricting the flow of liquid from the container to the dispensing or discharge member on the canting of the container and it is therefore a further object to so form the discharge or dispensing member as to restrict the flow of liquid therefrom, back to the container on the canting of the latter.

In the drawings forming a part of this specification and in which like numerals designate similar parts in the several views:—

Figure 1 is a vertical section through the soap dispenser showing parts in full lines.

Fig. 2 is a side view of the supporting bracket.

The valveless dispenser herein designed for the purpose of permitting a quantity of liquid soap to be discharged into the hand of the operator at the desired time, consists primarily of an attaching bracket 1, which

may be secured to the wall or some other suitable support by screws or appropriate fastenings 2. Extending horizontally from the bracket is a cylindrical stem 3, provided therein with annular grooves 4 and 5. This cylindrical stem or extension is extended beyond the groove 5 where it is provided with a longitudinal vent bore 6 having a lateral branch 7 for a purpose, to be hereinafter explained.

The discharge or dispensing member 8 constitutes a part of the present dispenser and on reference to Fig. 1 it is seen that this member consists primarily of a discharge nozzle 9 having a hollow cylindrical lateral sleeve 10. This sleeve fits over the cylindrical stem 3 from which it is free to revolve. In order to hold the sleeve against moving in a longitudinal direction upon the stem 3, I provide a screw 11 adjustably fitting in the sleeve and provided with an extension 12 which is projected into the groove 4. This arrangement is such that a swivel connection is formed between the mentioned parts for a purpose which will presently appear.

The nozzle 9 is provided with an interiorly threaded socket 13 which receives a correspondingly threaded neck 14 of a spherical liquid soap container 15. Fitting between the socket of the nozzle and the neck 14 is a packing disk 16 having an aperture 17 communicating with a bore 18 in the nozzle. The bore 18 enters the bore 6 as at 19 and on reference to Fig. 1 it will be observed that normal communication is thus established with the liquid container permitting the same to be properly vented.

The nozzle 9 of the discharge member is provided with a tube 20 extending in a vertical direction into the container. This tube opens into a passage 21 of the nozzle at one end and at the opposite end the tube is provided with a crown 22 having a central relatively small aperture 23. The crown of the tube 20 is spaced from the bottom of the container 15 so that liquid from the container may flow into the tube as clearly illustrated in Fig. 1.

The crown of the tube 20 is provided for the purpose of forming a restriction to any return flow of liquid within the tube back to the container 15 during the process of canting the container for the purpose of discharging the soap into the hand of the user.

The construction of the device herein

specifically referred to, is such that the hand of the user may be placed over the discharge end of the nozzle 9. Slight force may be exerted against the nozzle or against the 5 container 15 so as to move the latter to an inverted position upon the axis of the stem 3. The liquid in the container 15, except that which has passed into the tube 20 will then flow to the opposite end of the 10 container, while that which has passed into the tube will be free to flow into the hand of the user. At the time of the position of the parts to effect such operation, the sleeve 10 of the nozzle will be revolved on the stem 15 3 and the vent passage 7^a in the sleeve will be brought out of line with the branch 7 of the bore 6. The container 15 is then closed from the atmosphere and the liquid is held 20 against flowing or leaking onto the exterior surfaces of the device. In order to prevent possible leakage, the groove 5 carries a pack-

ing washer 24 which bears against the inner walls of the sleeve 10.

What is claimed as new is:—

A dispensing device comprising a stem 25 having a longitudinal vent bore provided with a lateral branch, a nozzle having a sleeve rotatably mounted on the stem and provided with a passage adapted to register with the said lateral branch when the nozzle 30 is directed upwardly and to be out of register therewith when the nozzle is directed downwardly, and a container attached to the nozzle, said nozzle having also a bore which communicates with the bore of the stem and 35 with the container.

In testimony whereof I affix my signature in presence of two witnesses.

MARK G. MELVIN.
